TOY TYPEWRITER

Sidney R. Bell, Stamford, Conn.

Application October 24, 1935, Serial No. 46,592

11 Claims. (Cl. 197—47)

The present invention relates to typing and is especially concerned with an improved and simplified toy typewriter comprising relatively few parts and adapted to be readily manufactured and assembled at a relatively small cost.

The invention has as one object the provision of an educational toy in the form of a simplified toy typewriter characterized by a pivoted arm having a rotatably supported dish shaped type carrying dial adapted to be manually settable to a predetermined position of selection and subsequently depressed towards and against a rectilinear platen to cast an ink impression on a sheet of paper.

The invention has as another object the provision of a functionally and structurally improved toy typewriter having a normally raised pivoted arm carrying a cup shaped guard provided with a manually rotatable type carrying dial and means for frictionally holding the arm in a set position during rotation of the dial relative to the guard.

The invention has as another object the provision of a novel toy typewriter having a self raising pivoted arm comprising a guard rotatably supporting a type carrying dial which includes means cooperating with a colored index associated with the guard for appropriately setting the rotatable dial to a predetermined position of selection.

The invention comprehends as another object the provision of a toy typewriter comprising a spring controlled depressible arm having a cup shaped guard surrounding a rotatable nested dial and spring actuated means for locking the dial in a predetermined position of selection.

The invention further contemplates as an object the provision of a toy typewriter characterized by a relatively light stiffened and reinforced type carrying rotatable dial adapted to be set and locked in a predetermined position of selection and self raising depressible means adapted to be moved toward a rectilinear platen to permit a selected portion of the dial to cast an ink impression against a sheet of paper supported on the platen.

The invention has as another object the provision of a toy typewriter having a guarded and a nested type carrying rotatable wheel or dial mounted on a depressible arm and complementary escapement means for laterally advancing the arm one step preparatory to each printing operation of the dial.

The invention has as a further object the provision of a toy typewriter having manually rockable means rotatably sustained by the base plate

thereof for advancing a sheet of paper step by step and in a direction towards a type carrying rotatable dial, and loosely and rotatably mounted checking means to prevent displacement of the sheet of paper in a counter direction during manipulation of the rockable means.

The invention comprehends as a further object the provision of a base plate defining a rectilinear platen supporting complementary escapement means and a spaced track for rectilinearly and laterally guiding a dial carrying pivoted arm, the complementary escapement means and the track constituting guide means or communicating elongated and aligned gaps to facilitate guiding of the sheet of paper interposed between the base plate and the track, and between the base plate and the rack.

The invention has as another object the provision of a toy typewriter characterized by a rectilinear platen adapted to receive the impact of a type carrying dial during each printing operation and strengthening means integrally depending from the platen to prevent flexing thereof along the line of printing.

The invention has as another object the provision of a toy typewriter further characterized in that the type carrying rotatable dial is provided with an annular strengthening rib cooperating with the guard of the dial to prevent tilting of the latter relative to the guard.

The invention contemplates as another object the provision of a simplified toy typewriter comprising a slideable carriage having a pivoted connection with a spring controlled arm carrying a guard to which is rotatably and concentrically mounted a dial having an annular embossed rim carrying a plurality of outwardly facing spaced type, the guard including flange means spaced from the dial to render the type of the latter inaccessible to touch on the part of the operator, the flange means, however, defining a gap to receive and permit a selected portion of the dial to face downwardly preparatory to the printing operation.

These and other features of the invention will be best understood and appreciated from the following description of the preferred embodiment thereof selected for purposes of illustration and shown in the accompanying drawing in which:

Fig. 1 illustrates in side elevation and partly in section the toy typewriter according to my invention.

Fig. 2 is a longitudinal plan broken view of Fig. 1.

Fig. 3 is a face view of the rotatable dial and its guard.

Fig. 4 is a fragmentary sectional view on the line 4—4 of Fig. 3.

5 Fig. 5 is a fragmentary sectional view on the line 5—5 of Fig. 3.

Fig. 6 is a sectional view taken on the line 6—6 across the rectilinear platen in Fig. 1.

10 Fig. 7 is a sectional view on the line 7—7 of Fig. 2 and

Fig. 8 is a perspective view of the slidable carriage.

15 The toy typewriter, generally denoted 10, comprises a rectangular table or base 11, a longitudinally disposed track 12, a slidable carriage 13, a pivoted arm of housing 14, a guard 15, a rotatable dial 16, paper feeding means 17, checking means 18 to prevent return displacement of a sheet of paper and complementary escapement 20 means including a weighted pawl 19 rotatably mounted on arm 14 and a longitudinally arranged rack 20 secured to base 11.

25 More particularly table 11 comprises an elongated sheet metal plate 23 having a peripheral depending flange 21 comprising a lower beaded edge 22 to prevent marring or scratching of the supporting surface on which the toy typewriter is placed.

30 Track 12 is a one piece sheet metal channel shaped member comprising an elongated flat horizontally disposed plate or wall 23' having vertically disposed depending sides 24 each having rectangularly shaped lugs 25 appropriately passed through correspondingly shaped openings in the 35 flat horizontal plate 23 of the base and subsequently turned inwardly and against the lower surface thereof, thus appropriately securing track 12 to the table or base to prevent relative displacement thereof.

40 For slidably guiding carriage 13 longitudinally of the table, track 12 integrally includes front and rear spaced and inwardly turned flanges 26 defining spaced longitudinal grooves 27 with the plate 23. The spaced grooves 27 slidably receive and 45 guide the spaced integrally depending angle irons or rails 28 extending from the upper horizontal wall 29 of carriage 13.

50 Extending upwardly from the wall 29 of the carriage 13 and integral therewith is a pair of spaced vertically disposed ears 30 each having a lug 31 struck inwardly thereof and towards each other to serve as fulcrum means for pivotally sustaining the yoke shaped housing or arm 14.

55 Specifically, however, each inwardly overhanging lug of the spaced ears 30 is pivotally mounted in an associated opening 32 of companion spaced sides 33 of arm 14, the ears 30 of the carriage closely straddling sides 33 but permitting relative pivotal movement of the arm, it being noted 60 that sides 33 of the pivoted arm 14 are integrally interconnected by an inclined wall 34 to constitute a housing while each of the sides 33 includes a lower depending corner shoulder or projection 35. These spaced shoulders 35 cooperate with the rear 65 stop flange 26 of track 12 to limit upward pivotal displacement of arm 14 which is normally retained in a raised or elevated position by a curved leaf spring 36 disposed within the housing constituted by arm 14.

70 When arm 14 is manually depressed, the free leg 37 of the flat leaf spring 36 abutting wall 34 is flexed downwardly and upon removal of such pressure, leg 37 automatically pivots arm 14 upwardly but such upward pivotal displacement is limited by 75 the coaction of spaced abutment shoulders 35

striking the rear flange 26. In connection with leaf spring 36, it will be observed that its lower leg 38 is rigidly anchored to the top horizontal wall 29 of the carriage.

5 Rigidly attached to the forward part of the pivoted hollow arm 14 is the cup shaped cylindrical guard 15 having its lower zone portion cut away to provide a relatively wide gap or mouth 39 for rotatably receiving a portion of the nested dish shaped type carrying dial 16.

10 To facilitate assembling of guard 15 to arm 14, the spaced sides 33 of the latter are each provided with inclined edges 40 and the rear wall 34 interconnecting sides 33 includes a longitudinal edge 41, the latter and edges 40 being disposed against 15 the rear circular wall 42 of guard 15. However, edges 40 and 41 include tabs or lugs 43 adapted to be passed through suitable openings in the rear wall 42 of the guard and thereafter turned or bent against the front face thereof, thereby forming the 20 rigid connection between the guard and arm.

As previously pointed out, dial 16 is rotatable relative to guard 15. To this end, the latter is provided with a forwardly extending annular and concentric nipple 43' projecting through an axially arranged circular opening 44' in the rearwardly extending annular hub or boss 44 integral with the circular inclined wall 45 of the dial. Subsequently the forward portion 46 of nipple 43' is upset to constitute an annular retaining flange 30 overlapping portions of hub 44 adjacent its bore. In other words, annular flange and its nipple 43' together with rear wall 42 of the guard provide an annular groove or bearing, the walls of which 35 rotatably support and guide hub 44 of the dial.

It should be noted that the rear inclined wall of 40 annular hub 44 is in movable contact with the guard and is retained in such relationship by the retaining flange 46. Hub 44 together with the rearwardly depressed annular rib or bead 47 function as means to space circular wall 45 of the 45 rotatable dial away from the rear wall of the guard, the annular rib 47 of the dial also serves to stiffen and reinforce the latter, and by employing this structural expedient lighter metal stock out of which the dial is formed may be utilized.

The frusto-conical rim or annular flange 48 of the dial is appropriately embossed or stamped to provide outwardly facing type 49 circumferentially arranged in spaced relation and forming 50 means in association with the spaced inking pads 50 which coat the type during rotation of the dial for printing on a sheet of paper (not shown) mounted on the horizontal wall 23 of the base, of course, after arm 14 has been manually depressed.

55 Each of the inking pads 50 is suitably retained in a sheet metal frame 51 integrally carried by a bent resilient arm 52 secured to rear wall 42 of the guard 15 by fastening means in the form of rivets 53. The inking pads 50 are thus disposed between 60 the guard and the type carrying rim of the rotatable dial and as the latter rotates, the inking pads 65 yieldingly bear against the moving type and coat the latter.

According to the invention, the forward face 65 of the rear inclined wall or disc 45 of the dial is provided with an annular and closed band of indicia consisting of letters of the alphabet 54, numerals 55 and other desired designations 58 as shown, each in radial registration with correspondingly identified type 49 of the rim of the 70 rotatable dial.

75 Interposed between the indicia band of the dial and the annular stiffening rib 47 is a closed annular zone of spaced perforations or indents 75

56 adapted to selectively interlock with an associated detent carrying spring arm 57 rigidly fastened to the rear wall 42 of the guard, that is, detent 59 of arm 57 is adapted to resiliently and 5 removably interlock with an indent 56 for holding the rotatable dial at a predetermined position of selection. This position is determined by rotating the dial to line up the selected character of the indicia band of the dial with a colored 10 front wall 60 of a forwardly projecting boss 61 of the guard. For example, where it is desired to print the letter "A", the dial is rotated until the letter "A" appears in alignment with the colored index wall 60 of boss 61 at which time the dial 15 is stopped and consequently detent 59 enters and interlocks with an opening 56, thereby holding the dial in a set position preparatory to manually depressing pivoted arm 14, it being noted that for each character as 54 or 55 there is provided 20 a radially aligned opening 56 in the annular zone of spaced perforations of the dial.

For selecting a desired character to be printed, the dial is first manually grasped and rotated until the selected character lines up with colored 25 wall 60. With the selection completed and the dial locked, it will be observed in Fig. 3, that the lower part of the dial is disposed within the gap or mouth 39 of the guard. In other words, the selected portion of the dial is outside of the rim 30 of the guard and spatially overhangs the latter, whereby the selected type faces downwardly and slightly above the horizontal wall 23 of the base.

Further in accordance with the present invention, wall 23 of the base is utilized to support a 35 sheet of paper against which the ink coated selected type of the rotatable dial is pressed to effect casting an ink impression thereon. In this connection, it will be observed that the paper holding and feeding means 17 comprises an actuator 63 40 embodying an elongated cylindrical rod 64 rotatably sustained on a pair of spaced upstanding perforated ears 65, struck out of the horizontal wall 23 of the base.

Rod 64 comprises an integrally flattened crank 45 66 adapted to be depressed by the fingers of the operator for rotating rod 64 whereby the spaced cylindrical rubber feed rolls 67 rigidly fastened to rod 64 may be correspondingly rotated. Normally crank 66 is held in a raised position by reason of a spring 68 having an intermediate portion 69 coiled about rod 64, one rectilinear leg 70 of spring 68 downwardly abutting wall 23, while another offset leg 71 thereof resiliently bears 50 against a lower face of the crank arm 66.

In this connection, it will be observed that offset leg or terminal 71 of spring 68 includes a laterally disposed part 72 normally abutting a shoulder 73 integral with an associated ear 65 which forms one supporting bearing for rod 64.

When downward finger pressure is applied to crank arm 66, rod 64 is rotated, consequently rotating the paper feed rolls 67 and since the latter yieldingly bear against a sheet of paper supported on wall 23, the sheet of paper is bodily moved rearwardly or towards the dial a predetermined distance on each complete downward stroke of the crank arm and the latter is stopped at the conclusion of its down stroke by the horizontal wall 23.

During each downward stroke of the crank arm, spring 68 absorbs a certain amount of energy, which is released upon removal of finger pressure from the crank arm. Consequently, the latter rises automatically and thus turns rod 64

in a reverse direction. It will be appreciated, however, that rearward displacement of the crank arm is limited due to abutment 72 of spring 68 striking the stop shoulder 73.

However, on the return of the crank arm to its 5 normally raised position means has been provided to prevent bodily forward or return displacement of the paper previously bodily advanced rearwardly. To this end, checking means 18 in the form of a pair of spaced cam shaped wedge 10 members of spring metal or rubber are loosely rotatably mounted on rod 64. Each of the cam shaped members has a weighted nose or wedge 15 frictionally cooperating with the upper surface of the sheet of paper to hold the latter stationary at a time when the crank is moving upwardly to its normally raised position at which time feed rolls 67 move in a direction counter or reverse to their rotation when the crank arm is depressed.

Upon each complete downward stroke of the dial preparatory to each printing operation thereof, the dial is advanced laterally one step to the right. For this purpose an escapement is provided. The escapement essentially consists of 25 complementary members characterized by rotatable pawl or latch 19 and the longitudinally disposed bar in the form of a rack 20 having its spaced teeth 76 facing upwardly. The rack is spaced from upper wall 23 of the base 11 to 30 leave a gap 77 through which the sheet of paper mounted on wall 23 is advanced rearwardly step by step, the rack 20 being secured to wall 23 by oppositely extending lugs 78 and 79 as is well understood.

Rotatably secured to a lug 80 bent from one side wall of arm 14 as to extend within the housing thereof is the pawl or lever 19. Particularly, however, pawl 19 has its intermediate portion rotatably carried by a rivet 81 fastened to lug 80. 40 The pawl is provided with a lower weighted and curved flared or tail portion 82 severally cooperating with the teeth of the rack to bodily advance carriage 13 and its pivoted hollow arm 14 step by step laterally to the right, consequently correspondingly advancing the dial.

The upper part of the rotatable weighted pawl 19 overhangs arm 14 and includes a rearwardly extending lug or shoulder 83 having two purposes, one to cooperate with an adjacent side 33 50 of arm 14 to limit normal downward displacement of the weighted portion of the pawl and two, serving as a finger piece for manipulating the pawl to disengage the latter from the rack if interlocked therewith or for clearing the rack 55 to permit manual and lateral displacement of the carriage relative to its guide track or base.

The upper horizontal wall 23' of the track 12 is spaced from the upper horizontal wall 23 of the base thereby providing an elongated relatively narrow gap 84 in communication with a correspondingly shaped gap 77 formed by the rack 20 and the upper horizontal wall 23 of the base 11, the communicating and aligned gaps 77 65 and 84 providing means for receiving and guiding the sheet of paper as it is advanced rearwardly step by step after successive manipulations of the crank arm. In Fig. 1, the arrow indicates the direction of travel of the paper rearwardly along 70 the base and after the desired printing is completed, the rearward margin of the paper has passed through gap 84 and extends beyond the rear part of the track, thereby readily permitting grasping of this part of the sheet by the operator 75

who pulls the sheet rearwardly and completely through and out of gap 84. In other words, gaps 77 and 84 constitute a transversely disposed guide slot for guiding a sheet of paper rearwardly relative to the base.

In operation, assuming, of course, a sheet of paper is mounted on wall 23 as to be advanced step by step upon operation of the crank arm, the operator now turns by finger pressure the dial relative to the guard. At the desired selection, the colored wall 60 appears in registration with an opening 56 of the annular zone of perforations. In this position, the dial is locked by the spring actuated detent 59 interlocking with another opening 56 of the zone of perforations.

Pursuant to the indicia selection and locking of the dial, the operator now applies a downwardly directed finger pressure on the rim of the dial at a point substantially in line with the colored wall 60 of the boss 61. Consequently arm 14 is pivotally moved in a downward direction relative to carriage 13 and pawl 19 enters a notch between a pair of teeth on the rack 20. On continued finger pressure applied to the selected part 25 of the rim of the dial, pawl 19 is caused to be rotatably displaced a few degrees, thus causing the pivoted arm 14 and its supporting carriage 13 to be bodily and laterally displaced one step to the right and downwardly. Hence the selected type of the dial contacts the paper and casts an impression thereon.

When, however, the dial is rotated relative to the guard, lateral displacement of the arm 17 and carriage 13 is prevented. For during the selection of a desired character, arm 14 is held in a raised position by the leaf spring 37. The energy of this spring causes shoulders or feet 35 of the arm to frictionally engage the rear rail 26 of the track 12. It follows therefore that in the normal raised position of the arm, the dial may be rotated without disturbing the set position of the arm.

Having applied the desired impression on the sheet of paper, manual or finger pressure is removed from the dial, and the arm 14 is automatically raised by spring 37. When arm 14 lifts, pawl 19 automatically shifts to its normal position by reason of its weighted tail part 32, thereby preparing itself to cooperate with a successive tooth of the rack on the following downward stroke of the pivoted arm 14.

In accordance with the invention, wall 23 which received the impact of the dial during the process of printing is rectilinear, that is, the central part 86 of wall 23, for the purpose of the present invention serves as the platen. Therefore to prevent downward sagging or deflecting of the platen 86 to provide a relatively rigid support to resist the force of the impact by the dial on the printing operation, top wall 23 is integrally provided with longitudinal spaced braces 87 struck out of wall 23 and disposed vertically and downwardly in parallel to the front and rear sides of the peripheral rim 21 of the base.

According to the present invention several parts may be made of sheet metal or light weight metal stock, such as aluminum, although the invention is not restricted to the type of material employed. It will be appreciated, however, that the typewriter herein disclosed comprises relatively few parts and can be readily manufactured and assembled at a relatively low cost.

It will be observed that the normally inclined rear wall 42 embodies a centrally arranged depending lip 42' serving as a stop adapted to

abut the paper on the platen on each down stroke of the pivoted arm on a settable spacing operation of the dial thereby precluding the possibility of transfer of any ink of adjacent type of the dial onto the paper. In other words, lip 42' strikes the paper on the platen during a spacing operation and hence the type of the dial is held out of contact with the paper during this operation although the pivoted arm has been depressed.

While the invention has been described in detail and many modifications and a specific application thereof have been referred to, the invention herein is not limited to such specific application and it is to be understood that all matter contained in the above description or shown in the accompanying drawing shall be interpreted as illustrative and not in a limiting sense.

I claim:

1. In a toy typewriter, a base having a track, a step by step displaceable carriage slidably guided by said track, a transversely disposed arm pivoted to said carriage, spring means for normally holding said arm elevated, and an indicia and type carrying dial rotatable relative to said arm, said arm and track having means to limit upward pivotal displacement of said arm, said spring means cooperating with said arm to cause the latter to abut said track and prevent lateral displacement of said arm during rotation of said dial.

2. In a toy typewriter, a displaceable arm having an indicia and type carrying rotatable dial, means for laterally guiding said arm, spring means for normally holding said arm elevated, means to limit upward pivotal displacement of said arm, and means to prevent lateral displacement of said arm during rotation of said dial.

3. In a toy typewriter, a guard, an indicia carrying dial rotatably and concentrically carried within said guard, inking means carried by said guard and detent means secured to said guard, said dial comprising a disc having a plurality of perforations and a type carrying rim, said inking means upon rotation of said dial adapted to coat the type of said rim, said detent means pursuant to rotation of said dial to a predetermined position cooperating with one perforation of said plurality to hold said dial in a predetermined position of selection.

4. In a toy typewriter, a guard having a portion thereof removed, a dial rotatably carried by said guard and having a part thereof movably extending beyond said removed portion, inking means carried by said guard and detent means mounted on said guard, said dial comprising a disc and a forwardly projecting rim, said disc comprising a plurality of spaced perforations and a plurality of spaced indicia in radial alignment with said perforations, said rim having a plurality of spaced type in radial alignment with corresponding indicia of said disc, said inking means upon rotation of said dial adapted to coat said type of said rim, said detent means cooperating with a perforation of said plurality to hold a selected and coated portion of said rim in said removed portion of said guard.

5. In a toy typewriter, a guard having a portion thereof removed and including a colored index, spring actuated detent means connected to said guard and a dial rotatably supported on said guard comprising a rearwardly disposed disc and a forwardly projecting rim including spaced type, said disc having a plurality of openings and spaced indicia in alignment with said openings and said type, said colored index being severally viewable through said perforations for setting

said type to a predetermined position, said detent means severally cooperating with said perforations to hold said dial in a predetermined position of selection.

5 6. In a toy typewriter, a spring actuated transversely disposed arm having a guard and an indicia and type carrying dial rotatably mounted on said guard, said dial having a rearwardly disposed strengthening rib to prevent tilting of said dial relative to said guard.

10 7. In a toy typewriter, a pivoted and spring actuated transversely disposed laterally step by step displaceable arm, a guard secured to said arm and having a portion thereof removed to define a gap, a dial rotatably carried by said guard and having a circumferential portion thereof movably receivable in said gap to overhang said guard, said dial having an annular reinforcing bead to prevent tilting of the dial relative to said guard and means 15 to prevent rotation of said dial relative to said guard.

20 8. In a toy typewriter, a platen, an arm, a type carrying dial rotatable relative to said arm, a channeled member disposed at the rear and longitudinally of said platen, and a carriage having spaced bent elements slidably guided by the marginal portion of said channeled member and including upstanding wings, said arm comprising a housing straddling said wings and pivotally supported by the latter.

25 9. In a toy typewriter, an arm, a platen, a channeled member spaced from said platen, a guard secured to said arm, a dial rotatably sustained by said guard, said channeled member having transversely spaced longitudinally extending marginal beads, a carriage having transversely spaced elements slidably guided by said beads and including upstanding substantially vertically

disposed wings, said arm comprising a housing adapted to enclose said wings, means for pivotally sustaining said arm relative to said wings, and spring means cooperating with said arm to normally hold the latter in a raised position.

5 10. In a toy typewriter, an elongated platen, a depressible arm, a substantially U shaped channeled member spaced from said platen, a guard secured to said arm and including a bearing, a type carrying dial rotatably sustained by said bearing, said channeled member having spaced longitudinally disposed marginally extending beads, a shiftable carriage having transversely spaced elements slidably guided by said beads and including upstanding substantially vertically disposed wings, said arm comprising a housing adapted to enclose said wings, means for pivotally sustaining said arm relative to said wings, and spring means cooperating with said arm to normally hold the latter in a raised position.

15 11. In a toy typewriter, a platen having an elongated rectilinear upper face, an arm, a channeled member having a lower substantially horizontally disposed wall spaced from said face, a guard fixed to said arm, an indicia and type carrying dial rotatably sustained by said guard, said channeled member having transversely spaced beads, a carriage shiftable longitudinally of said platen and having transversely spaced elements slidably guided by said beads and including upstanding substantially vertically disposed wings, said arm comprising a housing adapted to embrace said wings, means for pivotally sustaining said arm relative to said wings, and spring means cooperating with said arm to normally hold the latter in a raised position.

20 25 30 35 SIDNEY R. BELL.
